US00D846456S

(12) **United States Design Patent** (10) Patent No.: **US D846,456 S**
(45) Date of Patent: **** Apr. 23, 2019**

(54) **AIR GRILLE FOR CONSTRUCTION VEHICLE**

(71) Applicant: **BOMAG GmbH**, Boppard (DE)

(72) Inventors: **Roland Loew**, Klein-Winternheim (DE); **Christian Berg**, Völkenroth (DE); **Thomas Klein**, Wehr (DE); **Tobias Schönberg**, Oberelbert (DE)

(73) Assignee: **BOMAG GmbH**, Boppard (DE)

(**) Term: **15 Years**

(21) Appl. No.: **29/587,354**

(22) Filed: **Dec. 13, 2016**

(30) **Foreign Application Priority Data**

Jun. 13, 2016 (EM) 003188713-0018

(51) LOC (11) Cl. **12-16**

(52) U.S. Cl.

USPC **D12/163**

(58) **Field of Classification Search**

USPC D23/209, 260, 261, 317, 324, 325, 328, D23/330, 333, 335, 354, 364, 365, 366, D23/386, 406, 499; D12/12, 13, 14, 15, D12/38, 41, 42, 46, 93, 94, 99, 163, 164, D12/196, 210, 211; D15/10, 15, 22-26, D15/28, 30-31, 199

(57) **CLAIM**

The ornamental design for an air grille for construction vehicle, as shown and described.

DESCRIPTION

The sole FIGURE is a front elevation view of an air grille for construction vehicle showing our new design. The broken lines surrounding the air grille for construction vehicle depict a claim boundary that forms no part of the claimed design.

1 Claim, 1 Drawing Sheet
